UNITED STATES PATENT OFFICE.

MELBERN B. BULLA, OF EL PASO, TEXAS.

AUTOMATIC TRAIN-STOP.

1,203,970.

Specification of Letters Patent. Patented Nov. 7, 1916.

Application filed November 10, 1915. Serial No. 60,715.

To all whom it may concern:

Be it known that I, MELBERN B. BULLA, a citizen of the United States, and a resident of El Paso, in the county of El Paso and State of Texas, have invented a new and Improved Automatic Train-Stop, of which the following is a full, clear, and exact description.

This invention relates to railway appliances and has particular reference to safety appliances for railway trains, trolley cars or other analogous vehicles, and hence by the term locomotive as used herein I mean to cover any railway vehicle to which my improvements are adapted to be applied.

Among the objects of the invention is to provide appliances for use in connection with the ordinary air brake equipment, said appliances being controlled by a normally closed electric circuit holding the brake mechanism inactive but adapted to be released to set the brakes and shut off the power upon the breakage of said normally closed circuit either on the occasion of the locomotive passing a danger signal or because of the failure of the battery or other source of energy for said circuit by any means.

A further object of the invention is to provide improved facilities including an auxiliary magnet to insure that the brake air will be discharged for a sufficiently long time to stop the train even though the locomotive will have passed the point where the action of the brake setting appliances will have been initiated.

A still further object of the invention is to provide improved means for enabling the engineer to pass a danger point under orders or to flag a block and yet cause a record to be made of what he has done, whereby the railway officials will be informed as to whether or not the engineer is exceeding his authority, means being provided also to enable the engineer to reset the appliances to normal position after the locomotive may have been stopped by the automatic means.

With the foregoing and other objects in view, the invention consists in the arrangement and combination of parts hereinafter

described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a vertical longitudinal section of the safety appliance casing carried preferably within the locomotive cab adjacent the engineer, parts being in elevation and the electrical parts being in diagram; Fig. 2 is a side elevation in diagram of a locomotive, a signal adjacent the railway track, and the relation between the improved devices and the standard parts above referred to; and Figs. 3 and 4 are detail views of the 3-way valve in normally closed and open positions respectively, as further described below.

This invention is an improvement on my prior invention on which I filed an application for a patent on the 1st day of May, 1915, Serial No. 25,177.

The locomotive 10 is represented as operating along a railway track 11 toward or past a semaphore 12 which may typify any signal or switch device to be guarded by the locomotive appliances. Associated with the semaphore bar 13 is a movable switch blade 14 adapted to connect with a stationary contact point or blade 15 when the semaphore arm is set at danger. The contact 15 is connected by a wire 16 to a track rail, and the movable blade 14 is connected by a wire 17 to a stationary brush 20 adjacent the track. Under these conditions, therefore, the brush 20 is adapted to make electrical connection at the required time with the locomotive appliances through a shoe 21 carried by the locomotive when the brush is engaged by the shoe and the danger signal is set. The brush 20, however, is inactive when passed by a locomotive when the danger signal is set at clear.

Referring now more particularly to the locomotive appliances, I show at 22 a casing preferably of a closed nature and kept locked against unauthorized tampering, and

associated with the casing upon the locomotive is a locomotive battery 23 or an equivalent source of electrical energy.

- Within the casing are placed a primary 5 electromagnet 24 and an auxiliary electromagnet 25, the former having preferably a higher resistance than the latter. At 26 is indicated an armature of the primary magnet pivoted at 27. The free end of the 10 armature is adjustably connected to a stem 28 connected to the arm 29 of a 3-way valve 30. The extreme end of the armature is adapted to be acted upon by a set screw 31 tapped through a fixed bracket 32 15 whereby the armature may be locked against the magnet by the engineer in the event of failure of the apparatus and it is required for him to proceed on his course until repairs may be made. The armature, furthermore, has connected to it a spring 33 anchored at a fixed point 34 and tending to lift the armature away from the magnet. Under normal running conditions the magnet 24 is energized and thereby the valve 20 30 is held in position to close the air pipe 35 leading from the main reservoir 36. Associated with the valve 30 is an air vent pipe 37 normally open to the atmosphere, and also a T-connection 38 leading through 25 a pipe 40, on the one hand, to a pneumatic motor cylinder 41, and on the other hand through a pipe 42 to a pneumatic motor cylinder 43. The pipes 40 and 42 are normally opened to the atmosphere through 30 the connection 38 and valve 30. Within the cylinder 41 is a piston 44 having a rod 45 acting through a pin 46 upon the arm 47 of a normally closed valve 48 guarding the brake air pipe 49 leading from the train line 50. The rod 45 is also connected through a link 51 to a primary recorder 52. The piston 44 is normally held in its rear position by means of a spring 53 in the cylinder 41. The motor 43 is substantially 45 of the same character as the motor 41, but having its piston rod 54 connected to a throttle lever 55. The pipe 42 being normally in communication with the atmosphere provides that no obstruction to the 50 usual engineer's operation of the throttle lever will take place. It will be noted also that any leakage of compressed air from the pipe 35 past the valve 30 will be dissipated into the atmosphere.
- 55 For convenience of description I now refer to a plurality of binding posts represented at *a*, *b*, *c*, *d*, *e*, *f*, and *g*, and also contact points *h*, *i* and *k*. At 56 I show a block of insulation constituting a support 60 for two pairs of contact springs 57, 57' and 58, 58', the latter pair being preferably longer than the former and all co-operating with a switch blade 59 pivoted at 60 at the bottom of the casing and having a

depending handle 61 within reach of the 65 engineer. Although the diagram in Fig. 1 indicates the contact springs all on the same side of the switch blade, it will be understood that the springs of each pair may be arranged on opposite sides of the blade. 70 The blade 59 is electrically divided by insulation 62 between the two pairs of springs. The blade, furthermore, is adapted to occupy any one of three positions indicated at *A*, *B* and *C*, the normal position being 75 that shown at *A* and so maintained by virtue of a spring 63 anchored to the bracket 32.

The binding posts *a* and *b* are respectively connected to opposite sides of the 80 magnet 24 by wires 64 and 65, and a wire 66 connects the binding post *b* with one side of the battery 23. Wires 67 and 74 connect the battery 23 and shoe 21 with the front contact spring 58. The rear contact spring of the same pair is connected by a wire 68 to the binding post *e*. The magnet 24 is thus normally energized from the battery 23, the energy passing through the wire 74, shoe 21 and wire 67, springs 85 58, 58', wire 68, binding post *e*, wire 69, switch armature 70, contacts *i* and *k*, wire 71, binding post *f*, wire 72, binding post *a* and wire 64 on one side, and wire 66, binding post *b* and wire 65 on the other 95 side. In this condition the switch armature 70 is held by the spring 73 away from the magnet 25, this magnet being dead.

The moment the contact shoe touches the brush 20, when the danger signal is set, 100 energy from the battery 23 will pass through the wire 17, brush 20, shoe 21, wire 67, contact springs 58, 58', wire 68, binding post *e*, wire 69, armature 70, contact points *i* and *k*, wires 71 and 72, binding post *a*, 105 wires 64, 65 and 75, binding post *c*, wire 76, magnet 25, wire 77, binding post *d*, wire 78, binding post *g*, wire 79, contact springs 57, 57', and wire 80 to the ground. This momentary impulse given to the magnet 25 110 throws the switch armature 70 so as to bring the contact points *h* and *i* together, thereby breaking the circuit through the magnet 24. Even though the shoe 21 will quickly have passed the brush 20, the power 115 of the magnet 25 will be continued from the battery 23 as follows: wires 74, 67, springs 58, 58', wire 68, binding post *e*, wire 69, armature 70, contacts *h* and *i*, wire 81, binding post *g*, wire 78, binding post *d* 120 and wire 77 on one side, and wire 66, binding post *b*, wire 75, binding post *c* and wire 76 on the other side. This condition of the two magnets will continue until broken by operation of the engineer.

When the magnet 24 is thus deenergized, the spring 33 causes the valve 30 to move from the position shown in Fig. 3 to that of

Fig. 4, closing the vent pipe 37 and permitting the compressed air to pass from the pipe 35 into the T-connection 38 and thence into the two pneumatic motor cylinders 41 and 43. The design of the pipes and valve connections, therefore, will determine the rapidity of automatic stopping action. When the piston 44 is forced forwardly, the valve arm 47 will be moved in a clockwise direction, as shown in Fig. 1, to set the brakes. Likewise the throttle lever 55 will be thrown to the closing position and a record of the incident will be made on the recorder 52.

To reset the apparatus and release the brakes, the engineer will move the switch blade 59 to the C position, thereby breaking the connection between the springs 58, 58', and breaking the circuit through the auxiliary magnet 25 and permitting the spring 73 to restore the connection between the contacts *i* and *k*. Immediately, therefore, upon the release of the switch blade 59 the spring 63 will restore it to normal position and re-energize the primary magnet 24, whereby the valve 30 will be turned to the closed position of Figs. 1 and 3. This movement by the engineer of the switch blade 59 will cause a corresponding actuation of the auxiliary recorder 82 through a link 83 extending between the blade 59 and the recorder arm 54.

In order to pass a danger signal under orders, the engineer may swing the switch blade to the mid or B position, breaking the connection between the springs 57, 57', but without breaking the connection between the other pair of springs. This movement of the switch blade will likewise be recorded on the recorder 82. The ground connection, however, being broken, the magnet 25 will be powerless to change the position of the switch armature 70 and hence the magnet 24 will not at this time be deenergized.

I claim:

1. In an automatic train stop, the combination of a compressed air pipe, a valve to normally close the same, a normally closed electric circuit including a magnet having an armature, connections between the armature and the valve whereby the valve is held closed, power means acting upon the armature tending to open the valve when the circuit is broken, said normally closed circuit including a pair of contact springs and a switch blade connecting them, and means to automatically break said circuit when a danger point is passed, said circuit breaking means including an auxiliary magnet adapted to be energized momentarily by passing a danger point, said auxiliary magnet having an armature carrying a movable contact point serving to establish a new circuit through said auxiliary magnet on the break-

ing of the normally closed circuit, said new circuit being adapted to be broken subsequently by the movement of said switch blade from between the contact springs.

2. In an automatic train stop, the combination of an air line, a valve normally closing the same, power means tending to open said valve, means including a normally closed circuit overcoming the normal tendency of the power means, means to automatically break said circuit when a danger point is passed, permitting the power means to open the valve, means under the control of the engineer for neutralizing the effect of the circuit breaking means, and independent recording devices connected respectively to said valve means and the means under the control of the operator.

3. In an automatic train stop, the combination of a compressed air pipe, a valve to close the same, power means tending to open the valve to set the brakes, means including a normally closed circuit and an electromagnet to overcome the power means and thereby hold the valve closed, a locomotive battery in said normally closed circuit, an auxiliary magnet, means in addition to said locomotive battery to energize and initiate the action of the auxiliary magnet when a danger point is passed and thereby break the normally closed circuit permitting the power devices to be effective to open the air pipe, connections being provided to cause the energy of the auxiliary magnet to be continued through the locomotive battery after the point of initiation is passed, means including a movable switch blade and contact springs coöperating therewith enabling the engineer to break the circuit through the auxiliary magnet to restore the parts to normal position, and a pair of independent recording devices connected respectively to said valve and said movable switch blade whereby the acts of opening the valve and causing the same to be restored to closed position will be independently recorded.

4. In an automatic train stop, the combination of an air line, a valve to normally close the same, automatically operated power means tending to open the valve, electric devices including a normally closed circuit acting to overcome the tendency of the power means, thereby holding the valve closed, said normally closed circuit including a pair of contact springs and a movable switch blade coöperating with the same, an auxiliary magnet, means to energize the auxiliary magnet and maintain it energized, the energizing being initiated by passing a danger point and subsequently continued through the same source of energy as is included in the normally closed circuit, the initiating means including a second pair of contact springs coöperating with the aforesaid

switch blade, said switch blade being movable to different distances to separate either one pair of contact springs to prevent the setting of the brakes or both pairs of contact springs to restore the parts to normal position after the brakes have been set, and recording means connected to said switch

blade to make a record of the movements thereof by the engineer.
